Prince

(57) **CLAIM**

The ornamental design for a sign cover, as shown and
described.

DESCRIPTION

FIG. 1 is a perspective view of a sign cover, showing my
new design;

FIG. 2 is a perspective view of a sign cover shown in an
environment of use;

FIG. 3 is a front elevational view of FIG. 1;

FIG. 4 is a rear elevational view of FIG. 1;

FIG. 5 is a left-side elevational view of FIG. 1, the right-side
elevational view being a mirror image thereof; and,

FIG. 6 is a top plan view thereof.

In FIG. 2, the sign shown in broken lines is environment and
forms no part of the claimed design. All other broken lines
show portions of the article that form no part of the claimed
design.

1 Claim, 4 Drawing Sheets
